(Cl. D52—3)

To all whom it may concern:

Be it known that I, Harold N. Kinne, a citizen of the United States, residing at Peoria, in the county of Peoria and State of Illinois, have invented a new, original, and ornamental Design for a Vending Machine Cabinet, of which the following is a specification, reference being had to the accompanying drawing, forming part thereof.

I claim:

The ornamental design for a vending machine cabinet, substantially as shown.

HAROLD N. KINNE.
